DESIGN FOR A DRESS

Charlotte Flusser, New York, N. Y.

Application March 9, 1939, Serial No. 83,445

Term of patent 3½ years

To all whom it may concern:

Be it known that I, Charlotte Flusser, a citizen of the United States, residing in New York city, in the county of New York and State of New York, have invented a new, original, and ornamental Design for a Dress, of which the following is a specification, reference being had to the accompanying drawing, forming part thereof.

Fig. 1 is the front view of a dress showing my design.

Fig. 2 is the rear view thereof.

Fig. 3 is an enlarged fragmentary view of the dress shown in Fig. 1 illustrating the vertical embroidery stitches and the horizontal embroidered floral bands of the blouse portion in detail.

I claim:

The ornamental design for a dress, substantially as shown and described.

CHARLOTTE FLUSSER.
